UNITED STATES PATENT OFFICE.

EDWARD C. HAWES, OF PROVIDENCE, RHODE ISLAND.

DESIGN FOR A STEAM-TRAP CASE.

SPECIFICATION forming part of Design No. 15,718, dated January 13, 1885.

Application filed November 3, 1884. Term of patent 14 years.

To all whom it may concern:

Be it known that I, EDWARD C. HAWES, a citizen of the United States, residing at Providence, in the State of Rhode Island, have invented and produced a new and original Design for the Outer Case of a Steam-Trap, of which the following is a specification, reference being had to the accompanying drawings, forming a part thereof.

10 The figure is a perspective view of my newly-designed case for a steam-trap.

The leading feature of my design consists in the hexagonal form of the heads of the trap-case.

15 A is the central portion of the case, which

is cylindrical in its general contour, the exterior diameter of the case being greater than the length of the same, and B B are the heads. These are hexagonal in form, as represented in the figure, and project on all sides beyond 20 the contour of the cylindrical body A.

I claim—

The design for a steam-trap case herein shown and described, the same consisting of a cylindrical body surface, A, and the projecting hexagonal head surfaces B B.

EDWARD C. HAWES.
